UNITED STATES PATENT OFFICE

WILLIAM D. KYLE, OF MILWAUKEE, WISCONSIN, ASSIGNOR TO LINE MATERIAL COMPANY, OF MILWAUKEE, WISCONSIN, A CORPORATION OF WISCONSIN

INSULATOR

Application filed August 30, 1930. Serial No. 478,894.

The present invention relates to electric insulators in general, and constitutes an improvement upon insulators of the type shown in my prior Patent No. 1,821,222 issued Sept. 1, 1931. While the insulator herein shown is of general application, it is particularly applicable for dead ending insulated drop wires and for use on secondary racks.

In electric wiring work it is customary for the wiring contractor to furnish the wire connections from the side of the building into the house. The power company extends a connection to the house from the pole carrying the power lines and at the same time it establishes a connection to the conductors located by the contractor on the side of the building and extending into the house. The incoming power wire is extended through an eye or perforation in an insulator or is wound around a groove in the insulator, and the span is drawn tight. The end of the wire is then bent back and twisted about the main part of the span wire to hold the same tight against the head of the insulator. A connection is then made between the span conductor and the wire extending along the side of the house. Heretofore, it has been necessary to solder the connection in order to secure a satisfactory joint having a low electrical resistance. It is a particular object of the present invention to provide an insulator adapted for dead ending a line wire, wherein the insulator is provided with a terminal whereby the desired connections may be made without the necessity of soldering the connection. While the insulator of the present invention is particularly useful for dead ending a line wire it is also capable of other uses and I do not wish to be limited to any particular use to which my insulator may be put.

In my above referred to application I show a secondary rack which is provided with an insulator of the kind having a terminal member mounted therein for facilitating the establishment of the electrical connections between a pair of wires, such as a line wire and a drop wire. In the present application I show another form of insulator for accomplishing the same end. The insulators in both cases are generally made of frangible

insulation, preferably porcelain, although the invention is not limited to the use of such material. In the present form of my invention I make my insulator in a substantially spool-like form, said insulator having a pair of disc-like projections at its opposite end. The portion of the insulator between the disc-like projections is rounded for receiving the wire to be tied. An additional disc is formed integrally with the insulator and is spaced from and parallel to one of the discs of the spool-like body portion. This last mentioned disc is preferably made of a somewhat larger diameter than the diameter of the other discs and the space between the two last mentioned discs provides a place for mounting a connector or the like. In order to facilitate the mounting of a terminal member upon the insulator this portion of the insulator is preferably made of a square cross section whereby the contact structure may comprise a three-sided strap which is clamped around the square section by means of a single bolt. Contact blocks may be mounted upon one or more sides of this three-sided square for receiving the ends of the conductors that are to be electrically connected together.

The insulator is formed with a longitudinally extending opening for facilitating the mounting of the same upon a secondary rack. This opening may be made circular to permit a turning of the insulator upon the shaft of the secondary rack, or it may be made of a square or other polygonal shape whereby the insulator is prevented from turning with reference to the mounting shaft.

In one embodiment of my invention the central opening for mounting the insulator is made circular and one of the outer discs of the insulator is provided with a slot into which one of the arms of the secondary rack fits for preventing rotation of the insulator upon the secondary rack. I prefer to locate this slot in the disc that is of an enlarged diameter. The terminal is mounted upon the spool side of this disc or flange, and since this disc or flange is of an enlarged diameter the terminal does not extend beyond the body of the insulator. The body of the insulator therefore prevents accidental contact of the

terminal block with other live or grounded parts, and at the same time it permits ready access to the terminal member for making or severing connections between the conductors. 5 Since the terminal member is located within the insulator, that is the flange-like members extend beyond the terminal, and it is not possible for the terminal to touch other parts it is not necessary to tape the connection in 10 order to guard against the swinging of the connection into contact with the building or with other grounded or live parts.

One of the advantages that my present invention has in common with the invention of 15 my above referred to application, is that it permits the power company to disconnect the line to the consumer outside of the building in a very efficient and simple manner.

Now, in order to acquaint those skilled in 20 the art with the manner of constructing and using a device according to my invention, I shall describe, in connection with the accompanying drawing forming a part of this specification, an insulator embodying the present 25 invention together with the method of using the same.

In the drawing:

Figure 1 is a side view of an insulator constructed in accordance with my invention;

30 Figure 2 is a sectional view of the insulator shown in Figure 1, said view being taken along the line 2-2 of Figure 1 and looking in the direction of the arrow;

35 Figure 3 is an end view of a modified form of insulator, said view also showing, in fragmentary form, the manner of mounting the same upon a secondary rack; and

Figure 4 is an end view of the insulator shown in Figure 3.

40 Reference may now be had more particularly to the insulator shown in Figures 1 and 2. The insulator 1 is made of frangible insulation preferably, although not necessarily, material such as porcelain or the like, and all 45 of the edges of the insulator are preferably well rounded, especially the edges around which a conductor may extend. The insulator comprises a spool portion 2 which merges into the side portions 3 and 4. The 50 side portions 3 and 4 constitute extended discs or flanges. The disc or flange portion of the insulator, as well as the spool portion thereof, are of circular cross section. An extended circular disc 8 of somewhat larger diameter than the disc 3 is formed integrally with the insulator and spaced from the disc portion 4 thereof. The disc member 8 is connected with the rest of the body of the insulator by means of a portion 10 of a square or other polygonal shape, this portion being formed integrally with the rest of the insulator. The insulator is formed with a central opening 15 extending longitudinally of 55 the spool member 2, said opening being pro-

vided to facilitate the mounting of the insulator.

The insulator shown is provided with a connector for facilitating the establishment of electrical connections between the wires terminating at the insulator. This connector comprises a strap 18 which is shown as comprising three legs in the form of an open rectangle. The outer legs 19 and 20 of the frame member 18 may be slipped over the outer side 70 of the rectangular portion 10 of the insulator and may be securely mounted in place by means of a single bolt 22 which may be passed through openings in the two legs 19 and 20. This strap is preferably made of copper or 75 other material of good electrical conductivity, although this may be dispensed with without departing from the spirit of the present invention. Connectors 25, 26 and 27 are 80 mounted upon the three sides of the strap 18. 85 These connectors may be of any preferred construction and as shown comprise merely a copper block having two openings 29 extending therethrough for receiving the bared ends of conductors that are to be electrically connected together, and are provided with screws 30-30 for holding the conductors in the grooves 29 in firm engagement with the body of the connector. Any preferred form of connector may be used. In a construction where- 90 in the strap 18 is made of copper or other ma- 95 terial of high electrical conductivity the two bared ends of the conductors that are to be electrically connected together may be ex- 100 tended into openings 29 in different ones of the connectors 25, 26 and 27, whereas if the strap is made of material which does not have 105 a high electrical conductivity then the two ends of the conductors that are to be joined together are extended into the openings 29 of the same connector block 25, 26 or 27.

The insulator 1 may be mounted upon a secondary rack of any approved construction, although it may be mounted in any other manner that may be desired. A suitable sec- 110 ondary rack for use in connection with my improved insulator is shown in my Patent No. 1,524,141, issued January 27, 1925. A portion of the rack is shown, diagrammati- 115 cally, in Figure 1. The rack comprises a 120 metallic base 34 which may be of any ap- 125 proved construction and which is provided with a number of upstanding arms of which two, indicated at 31 and 32, are shown in Figure 1. The insulator is mounted between the arms 31 and 32 by means of a shaft 33 which extends through openings in the arms 31 and 32 and through the opening 15 in the insulator. This shaft extends through simi- 125 lar openings in other arms mounted upon the same base 34 and may support other insulators similar to the insulator 1.

In Figure 3 I have shown a secondary rack upon which is mounted an insulator of a construction differing somewhat from the in- 130

sulator shown in Figures 1 and 2. In so far as this insulator is the same as the one previously described similar reference numerals have been used to indicate similar parts. 5 This insulator differs from the one previously described in that here the flange or disc-shaped end 4', which corresponds to the portion 4 of Figure 1, is of a diameter equal to the diameter of the flange or disc-like end 3. 10 In addition, the disc or flange member 8 is provided with a slot or recess 40 which overlies the arm 31. The slot 40 straddles the leg 31 of the secondary rack and thus holds the insulator against turning. This insulator is provided with a connector of a construction such as has been described in connection with the insulator shown in Figure 1. 15 In this case, as in the previous case, the connector is mounted in the groove between the flange or barrier 8 and the flange or barrier 4'. This groove, in the present instance, is of such a depth that the connector lies substantially entirely within the groove with none of the connector parts extending beyond the flange or barrier 4'. In the structure shown in Figure 3 it is possible to have a more pronounced or deeper curvature at the spool portion 2 due to the fact that the section 8 now overlaps the leg of the rack and accordingly gives a little more room to work in and obtain the desired proportions of the porcelain. The higher barrier 4' of this form of insulator as compared with barrier 4 of the insulator shown in Figure 1 is an additional 25 advantage.

In compliance with the requirements of the patent statutes I have herein shown and described a few preferred embodiments of my invention. It is, however, to be understood that the invention is not limited to the specific constructions herein shown, nor to the specific use to which they may be put, both of the above being shown and described merely for illustrative purposes.

45 What I consider new and desire to secure by Letters Patent is:

1. An insulator comprising a pair of parallel disc-like members of insulation joined by a central portion extending between them, and a terminal member secured to the central portion and extending outwardly of the central portion by an amount less than the distance from the central portion to the periphery of the outer disc member.

50 2. An insulator comprising a spool of insulating material, said spool having a peripheral groove for holding a wire on the insulator when the same is looped around the groove, said insulator having a second groove, and a terminal mounted in the second groove and substantially entirely within the confines of the sides of the second mentioned groove.

55 3. An insulator comprising a spool of insulating material, said spool having a cen-

tral longitudinal opening for mounting the same and having a peripheral groove for holding a wire on the insulator when the same is looped around the groove, said insulator having a second groove, and a terminal 10 mounted in the second groove and substantially entirely within the confines of the sides of the second mentioned groove.

4. An insulator comprising a spool of insulating material, said spool having a central 75 opening for mounting the insulator and having a peripheral groove for holding a wire on the insulator when the same is looped around the groove, said insulator having a second groove, and a terminal member 80 mounted in the second groove and substantially entirely within the same, the grooves being defined by flange-like extensions with the flange on the outer side of the second groove of a larger radius than the other flanges.

5. A secondary rack construction comprising a supporting base, a pair of parallel arms extending therefrom, and a combined insulator and terminal non-rotatably mounted between said arms, said combined insulator and terminal comprising a spool of frangible insulating material having a groove formed therein for the reception of a conductor, a second groove formed therein and a terminal member carried in said second groove.

6. A secondary rack construction comprising a supporting base, a pair of parallel arms extending therefrom, and a combined insulator and terminal non-rotatably mounted between said arms, said combined insulator and terminal comprising a spool of frangible insulating material having a groove formed therein for the reception of a conductor, a second groove formed therein, a terminal member carried in said second groove, and a disc-like piece of insulation defining the outer side of the groove and spacing the terminal from the adjacent arm of the rack.

7. A secondary rack construction comprising a supporting base, a pair of parallel arms extending therefrom, and a combined insulator and terminal non-rotatably mounted between said arms, said combined insulator and terminal comprising a spool of frangible insulating material having a groove formed therein for the reception of a conductor, a second groove formed therein, a terminal member carried in said second groove, and a disc-like piece of insulation defining the outer side of the groove and spacing the terminal from the adjacent arm of the rack and having a formation on the outside thereof cooperating with the adjacent arm to prevent turning of the insulator on the rack.

8. An insulator having circular end flanges and a circular intermediate flange, a continuous smooth peripheral groove devoid of sharp edges and located between the intermediate flange and one of the end flanges, and

a second peripheral groove formed between the intermediate flange and the other end flange, said second groove being of a non-circular shape.

- 5 9. An insulator having circular end flanges and a circular intermediate flange, a continuous smooth peripheral groove devoid of sharp edges and located between the intermediate flange and one of the end flanges, a
10 second peripheral groove formed between the intermediate flange and the other end flange, said second groove being of a non-circular shape, and a terminal clamped in said second groove.
15 10. An insulator comprising a unitary body of insulation having two parallel flanges with a conductor receiving groove between them, a third flange parallel to the other flanges and spaced therefrom to define a terminal receiving groove, said insulator having a perforation extending longitudinally therethrough centrally of the flanges for receiving a mounting rod, and a preformed irregular configuration on the outside of an outer flange for cooperating with a rod support to prevent turning of the insulator.
20
25

In witness whereof, I hereunto subscribe my name this 27 day of August, 1930.
